Primary Examiner — David Muller*Assistant Examiner* — Nathan Johnston(74) *Attorney, Agent, or Firm* — Rabin & Berdo, P.C.(57) **CLAIM**
The ornamental design for an intravenous catheter, as shown and described.**DESCRIPTION**

FIG. 1 is a perspective view of a catheter for an intravenous catheter showing my new design;

FIG. 2 is a front view thereof;

FIG. 3 is a rear view thereof;

FIG. 4 is a top plan view thereof;

FIG. 5 is a bottom view thereof;

FIG. 6 is a right side view thereof;

FIG. 7 is a left side view thereof; and,

FIG. 8 is a reference view thereof.

The features shown in broken lines form no part of the claimed invention.
